UNITED STATES PATENT OFFICE.

EMORY UPTON, OF BENTON HARBOR, MICHIGAN, AND LOUIS C. UPTON, OF LA GRANGE, ILLINOIS, ASSIGNORS TO UPTON MACHINE CO., A CORPORATION OF MICHIGAN.

POWER-TRANSMITTING DEVICE.

1,106,903.

Specification of Letters Patent. Patented Aug. 11, 1914.

Application filed January 17, 1911. Serial No. 603,058.

To all whom it may concern:

Be it known that we, EMORY UPTON and LOUIS C. UPTON, citizens of the United States, respectively residing at Benton Harbor, in the county of Berrien and State of Michigan, and at La Grange, in the county of Cook and State of Illinois, have invented certain new and useful Improvements in Power-Transmitting Devices, of which the following is a specification.

Our invention relates to improvements in power transmitting devices, and has especial reference to transmitting devices for use in association with clothes washing and wringing machines.

One of the objects of our invention is to provide a simple, durable, easily running, and practically noiseless power-transmitting mechanism, whereby power may be transmitted from a constantly rotating motor to a plurality of machines to be driven, requiring oscillating intermittent rotary and reversible motion, distributing the proper motion to the respective devices, and means of control whereby said devices may be independently operated and the direction, extent, and character of motion thereof readily governed.

Another object of our invention is generally to improve the details of structure of the class of devices referred to.

Further objects of our invention will become apparent to persons skilled in the art from a consideration of the specification taken in conjunction with the drawings, wherein—

Figure 1 is an end elevation of a washing machine with the device appended thereto; Fig. 2 is a similar enlarged view with parts of the structure broken away and the main drive wheel removed for clearness of illustration; Fig. 3 is a side elevation of the device, showing some of the parts in section; Fig. 4 is an enlarged sectional view on line 4—4 of Fig. 2, showing parts broken away and other parts in section; Fig. 5 is a sectional view taken on line 5—5 of Fig. 2; Fig. 6 is a sectional view taken on line 6—6 of Fig. 2; Fig. 7 is a longitudinal sectional view of the clutch mechanism for disengaging the oscillating clothes receptacle from the main shaft; Fig. 8 is a sectional view taken on line 8—8 of Fig. 7; and Fig. 9 is a sectional view of the clutch-moving lever and parts for operating the clutch shown in Figs. 7 and 8.

In all of the views the same reference characters indicate similar parts.

In the particular washing machine with which our transmitting mechanism is shown to be associated the suds receptacle 10 is comprised of a structure consisting of wooden side walls 11—11', and a curved, preferably metallic, bottom wall 12, having, preferably, a metallic cover 12'. The structure is supported upon four legs 13—13, provided with cross pieces 14 and 15, near their bottom ends. The clothes receptacle or holder 16 is preferably composed of a curved perforated metallic wall 17 having preferably wooden walls 18, being slightly flattened at its top, and provided with a preferably wooden cover 19, hinged as at 20. The curved side walls 17 are preferably perforated as at 21, and provided with interior ribs, 22, spaced apart at intervals. Secured at the rear end of the clothes receptacle, and axially therewith, is a gudgeon, 23, preferably a projecting casting for rotary engagement with a supporting casting 24, secured to the side wall 11'. At the other end of the clothes receptacle is a generally similar casting 25 provided at its projecting axis, as at 26, with a flat plate for engagement with an operating mechanism, to be hereinafter described.

Secured to the upper edge of the structure is a clothes wringer, 27, provided with the usual rollers 28 and 29 and having a power shaft 30 projecting therefrom.

At the upper edge of the wall 11, of the suds-retaining receptacle is a laterally projecting part 31, to which is secured a vertically projecting part 32, forming a partial housing under or within which most of the power transmission mechanism is contained, the latter being secured to the wall 11 and the parts 31 and 32.

A projecting boss, 34, provides a bearing stud 35 for the main drive member 36, which in this case is preferably a sheave adapted to be driven by a rope or belt 37. Secured to the sheave, as by means of a pin 38, is a pinion gear 39. The transmitting sheave 36, and the pinion 39, are retained in place on the bearing stud 35 by means of the screw 40. The pinion makes transmitting engagement with a gear wheel 41, which is secured on the stud shaft 42 by means of the screw 43. The stud shaft 42 is secured in the casting 33 in a rearwardly projecting boss 44 by 110

means of a pin 45, thus securely holding the shaft 42 in stationary and rigid position.

Secured to the gear wheel 41 is a bevel gear 46, as by means of a pin 47. The gear wheel 41 and the beveled pinion 46 are to be freely revolved on the projecting end of the stud shaft 42. Outwardly projecting from the plate 33 are shaft bearing brackets 48 and 49, 50 and 51 (Fig. 2).

10 A shaft 52 is contained in the bearing 48 to the projecting end of which is secured a beveled gear 53, and to which is also secured a spur geared pinion 54. Coaxially arranged with the shaft 52 is a somewhat 15 longer shaft 55 having bearings in the bracket 49, to the end of which shaft is secured a similar beveled gear wheel 56. The beveled gear wheel 46 makes constant driving engagement with the beveled gear wheels 53 and 56, and when rotated turns both the latter two gear wheels in opposite directions. Secured to the end wall 11 by screws 57 is a plate 58 containing a projecting bracket providing a shaft bearing 59. Within this bearing is a shaft sleeve 60, Fig. 7, to the outer end of which is secured a beveled gear wheel 61. The opposite end of the sleeve 60 is expanded into a disk 62, provided with notches 63 in its periphery. A coacting clutch member 64 connects the shaft 55 to the sleeve 60. The disk 62 of the sleeve 60 forms one element of the clutch, the other element is slidably movable upon the shaft 55 and comprises a fixed sleeve 65, secured to the shaft 55 by means of a feather or key 66. The sleeve 65 is provided with two grooves on opposite sides of its diameter in which freely slide the connecting feathers 67.

Loosely mounted on the sleeve 65 is a ring 68, provided with an annular groove 69. The feathers or keys 67 are secured to the ring 68, as by means of pins 70. Loosely lying in the grooves 69 is a shifting fork 71, provided with a boss 72 on its upper end and secured to a rod 73, the rod being supported in bearing and depending brackets 74 with its end 75 slightly turned at a substantial right angle, and having loose engagement with a shifting lever 76, Fig. 9, the latter being pivotally supported on the upright 32 by means of the screw 77 passing through a plate 78 which is properly secured to the upright 32. A spring-pressed tapered sliding stud 79 makes frictional bearing 85 contact on either side of the lever 76 when the latter is thrown in a direction to engage the shifting clutch member 64, or to disengage it from the coöperating member, so that the shifting lever will be thereby retained in the position in which it has been placed. The clutch member 64, by the operation of the shifting lever 76 controls the operation of the clothes retaining receptacle 16.

65 The mechanism which operates the oscil-

lating, clothes-retaining receptacle, through the agency of the constantly rotating shaft 55 will now be described.

The casting 58, Fig. 6, provides an inwardly projecting hollow tapering boss 80 in which a stud shaft 81 has rotary bearing. Secured to the shaft 81, as by a key 82, is a bevel gear 83. The shaft 81 has an outer bearing 84 in the yoke piece 85, which is preferably an integral part of the plate 58. To the outer end of the shaft 81 is secured a crank arm 86, having a crank pin 87 on its free end. An outwardly squared bearing block 88 surrounds the crank pin 87, and is provided with two conical projections 89 and 90. A pitman rod 91, Fig. 2, is pivotally connected to a sliding rack 92, as by a screw 93, and contains in its other end a slot 94, in which the squared bearing block is prevented from turning but is free to move therein longitudinally. A screw 96 takes in the end of the crank pin 87, and by means of the washer 95 holds the pitman rod 91 and the squared bearing block in operative position with relation to the crank pin. At 90 opposite ends of the slot 94, in the pitman rod, and within said slot, are conical or nippled projections 97 and 98, coöperating with the similar devices 89 and 90 for holding the springs 99 and 100 in their respective positions within the slot. These are tension or take-up springs to admit of positive definite motion of the crank arm with relation to the variably moving sliding rack 92. Brackets 101—102 support the rack 100 guide 103, in which the rack 92 is freely moved when the crank arm 86 is rotated.

Meshing with the rack 92 is a segmental gear 105 secured to a shaft 106, as by means of a set screw 107. Secured to the wall 11 by means of screws 108 is a circular plate 109, Fig. 5, from which outwardly projects a hollow bearing stud 110, which forms a bearing for the oscillating shaft 106. The shaft 106 is provided with an enlarged end 111, containing an elongated slot 112, in which the flattened gudgeon 26 of the clothes-containing receptacle 16 rests, and by this means the clothes receptacle is oscillated when the shaft 106 is oscillated by the mechanism intervening between the constantly rotating shaft 55 and said clothes receptacle, in a manner clearly apparent. An elongated slot 112 provides a means for conveniently removing the clothes-containing receptacle from the suds receptacle and the elongated or flattened gudgeon 26, in the slot 112, provides a positive means through which power may be transmitted. A wearing plate 112' protects the wooden wall 11 115 from excessive wear.

The mechanism which we have described may be operated by any convenient power, such as a gas engine, or an electric motor, the latter being indicated by 115, through 130

the instrumentality of a belt 37, and the power sheave 36.

We will now describe that part of the power transmission device necessary to operate the wringer.

In the rotation of the wringer rolls, it is sometimes required that they shall be turned in a given direction and at other times in an opposite direction to suit the exigencies of the case. We provide a power transmission means by which the rolls may be rotated in either direction by the simple shifting movement of a clutch lever. To the shafts 52 and 55 are connected the spur gears 117 and 118, respectively, by keys or otherwise, so that the said spur gears 117 and 118 are fastened to the respective shafts and will be positively turned thereby. In the bracket bearings 50 and 51 are supported two coaxially arranged shafts 120 and 121 respectively, and surrounding said shafts, and freely rotating thereon are sleeves similar to sleeve 60 to which are connected spur gears 122 and 123, respectively, said spur gears having driving connection with the spur gears 117 and 118 respectively.

When the bevel gear 46, secure on the shaft 42, is rotated with the spur gears 117 and 118, it turns the shafts on which they are secured through the bevel gear 53 and 56 in opposite directions, and through the respective gears the shafts 120 and 121 are rotated in opposite directions. A clutch 125, similar in all essential respects to the clutch 64, heretofore described in detail, is located between the spur gears 122 and 123. On each side of the central clutch member is a sleeve overlying the respective shafts 120 and 121 and provided with engaging notches similar to the notches 63 in the sleeve 60. To these sleeves the geared pinions 122 and 123 are respectively secured. The clutch ring 126 is circumferentially grooved as at 127, similarly to the groove 69 made in the clutch ring 64, heretofore described. The clutch ring 126 also carries two slideable keys 128 and 128', shown in dotted lines in Fig. 4, adapted to slide over the underlying supporting sleeve and for clutching engagement with the notches made on diametrically opposite sides of the rotating sleeve members to which the respective geared pinions 122 and 123 are secured. When the clutch members are in the position shown in Fig. 2, the respective key or feather members are not in engagement with the notches of either of the sleeve clutch members and therefore, the pinions 122 and 123 will continue to be idly driven by the respective pinions 117 and 118. A fork member 129 is contained in the annular groove 127 of the clutch ring 126 and is secured to a clip 129' which is slidably supported on shaft 73. The yoke 128 may be reciprocated by means of a controller lever 131, which is pivoted at 132, and to the

lower end 133 is pivotally connected to link 134, which latter is pivotally connected, by means of a screw 130, to the clip 128, so that when the lever 131 is moved backward or forward the clutch ring 126 is laterally moved to engage the respective clutch member associated with the gear pinions 122 and 123, as the case may be, so that the wringer, which is driven by the shaft 120 may be rotated in either direction depending upon the position of the clutch ring member with respect to the sleeve members, which are controlled by the shifting lever 131. In bracket bearing 135, which is secured to the leg 13 of the structure, the shaft, 120, finds bearing. On the outer end of the shaft is a sprocket-chain wheel, 136, securely fast to the said shaft.

Upon bracket 138, Figs. 1 and 4, is mounted a shaft 139 carrying on its outer end a sprocket gear wheel 140 and on its inner end a slotted sleeve 141, for engagement with the shaft 30 of the wringer 27. The pin 142 enters the slot in the sleeve and is a means by which the wringer roll may be positively driven from the shaft 139, and it further provides a convenient means by which the wringer may be readily and quickly detached from the driving mechanism. The sprocket wheels 136 and 140 are connected by means of a sprocket chain 143. A housing 145 protects the sprocket chain, gears, and shafts. A protecting apron 148, preferably of sheet iron is hinged as at 149 to the frame 32 to protect the transmitting mechanism from damage resulting from water or from contact with moving objects. A strip of water proof flexible material 150, such as rubber, is attached to the frame 32 as by tacks 151 and overlies the joint between the frame and apron to shed the water that would otherwise find its way behind the apron and injure the machinery contained within the housing partly provided by said apron. Arch-shaped stops, 152, are provided to hold the said apron out of direct contact with the underlying transmission machinery.

It will be observed that when the clutch members are in the positions shown in Fig. 2, the motor may be rotated continuously without driving the washing apparatus or the wringer, and that either of these devices may be driven independently of each other and that the direction of rotation of the wringer may be quickly reversed, without interfering with the operation of the washer.

While we have herein illustrated a specific embodiment of our invention, as associated with a washing and wringer machine, it will be apparent that the same may be used in numerous other environments where similar transmission of power is desirable,

and that many changes may be made in the parts of the transmission device without changing its advantageous operation as herein disclosed and without departing 5 from the spirit of our invention and the scope of the appended claims.

What we claim is:

1. In a device of the character described, a constantly rotatable power shaft, a beveled 10 gear thereon, a train of gears on each side of the said beveled gear, each train carrying a coöoperating beveled gear engaging the first mentioned beveled gear on opposite sides of its axis, a device to be rotated, a 15 power-transmitting means adapted for connection to either of said trains of gears, and a clutch between said trains of gears for

connecting either of said trains to the said power-transmitting means.

2. In a device of the character described, a stationary structure, power transmission mechanism secured to a vertical wall of said structure, an overhanging projecting wall from said vertical wall, and an apron hinged to the outer edge of said projecting wall to partially house said transmission mechanism. 20 25

In testimony whereof we hereunto set our hands.

EMORY UPTON.
LOUIS C. UPTON.

In the presence of—

FORÉE BAIN,
MARY F. ALLEN.
